UNITED STATES PATENT OFFICE

108,985

DESIGN FOR A DOUBLE BARREL FIREARM

Edwin Pugsley, New Haven, Conn., assignor to
Winchester Repeating Arms Company, New
Haven, Conn., a corporation of Maryland

Application June 26, 1937, Serial No. 70,065

Term of patent 14 years

To all whom it may concern:

Be it known that I, Edwin Pugsley, a citizen of the United States, residing at New Haven, in the county of New Haven and State of Connecticut, have invented a new, original, and ornamental Design for a Double Barrel Firearm, of which the following is a specification, reference being had to the accompanying drawing, forming part thereof.

Fig. 1 is a view in side elevation of a double barrel firearm showing my new design; and

Fig. 2 is a top or plan view thereof.

The double barrel firearm of the present novel design is characterized by a frame having paral-

lel side-walls free of protuberances and spaced apart a distance substantially equal to the full width of the rear portion of the double-barreled barrel-unit; and a buttstock which is substantially concave throughout its full length on each of its respective opposite side-walls when viewed from above and which concave side-walls extend forwardly in unbroken lines from the grip-portion of the buttstock to the said parallel side-walls of the frame.

I claim:

The ornamental design for a double barrel firearm substantially as shown and described.

EDWIN PUGSLEY.
